FELLING MACHINE

Mario Buono, Port Washington, N.Y.

Application August 11, 1953, Serial No. 373,574

2 Claims. (Cl. 112—178)

My invention relates to a new and improved chain-stitch sewing machine for doing felling sewing.

It is necessary to form felling stitches in many important classes of sewing operations, in which the work consists in whole or in part of a plurality of superposed layers. In such cases, the felling stitches overlap the edge of the top layer and said felling stitches extend through the top layer of the work and through the next adjacent lower layer of the work.

Felling stitches are often used to sew a lining to drapery material, which is usually thicker than the lining.

Blind felling stitches are used extensively, to sew a lining to the sleeve of a garment. In doing this work, a tubular cloth sleeve body is first sewed, and said pre-sewed tubular body is doubled at its front edge, so that it has an inner cylindrical sleeve or body flap at its front edge. The lining is sewed to the tubular sleeve body, while said sleeve body is temporarily turned inside out, so that said cylindrical sleeve or body flap is then at the outside of the turned sleeve body. The body of the lining is usually doubled at its front edge, so that said lining body has an inner lining flap. This lining flap of the doubled lining is applied to the outer face of the exposed sleeve flap or body flap, so that the common front edge of the two lining layers overlaps the inner edge of the body flap. The lining is sewed to the body flap, but not to the body of the sleeve, by means of felling stitches which overlap the common front doubled edge of the two lining layers. These felling stitches are designated as blind felling stitches because they are invisible when the tubular sleeve and its lining are turned back to normal position, because said felling stitches do not penetrate the sleeve body.

For more than fifty years, chain-stitch machines which have a curved needle and a looper and a work table have been extensively used in industry.

These machines are generally shown in many United States patents, such as the following:

Number: Date:

1,926,644—Sept. 12, 1933
 1,926,761—Sept. 12, 1933
 2,108,100—Feb. 15, 1938
 2,108,101—Feb. 15, 1938
 2,250,745—July 29, 1941
 2,355,904—Aug. 15, 1944
 2,514,837—July 11, 1950
 2,627,828—Feb. 10, 1953

In general, this type of machine has a work-support or work-plate. This work-support is pivoted to the frame of the machine, so that its top face may be vertically adjusted relative to the lateral path of the oscillating, curved needle. This work-support is provided with work-supporting fingers which are pivoted to said work-support, and the work or material is slidably supported on said fingers. A feed-dog intermittently feeds the work or material longitudinally away from the front of the machine.

2

A rib or other bight-forming member is operated to form an upward longitudinal bight or bend in the work, while the longitudinal feed of the work is temporarily stopped, and while the curved needle is temporarily out of the work. As viewed at the front of the machine, the lateral piercing stroke of the laterally oscillated curved needle has been generally from left-to-right, and its reverse lateral stroke in which the needle is moved out of said bight, has been from right-to-left.

Although this general type of machine has been well-known and extensively used for at least fifty years, it has not been used in doing felling, or such use has been very unsatisfactory, particularly in felling a lining to a sleeve. In general, this type of machine has moved the curved needle laterally from left-to-right, in the lateral piercing stroke of the oscillating needle. Hence, in sewing a lining to work which consisted of a sleeve, as one example, it was necessary to force the entire tubular sleeve body on the work-support or work plate, with the front edge of the sleeve body at the left of the operator at the front of the machine. This was impossible or so difficult as to make it impossible to use this type of machine for felling a lining to a sleeve, and also for doing many other types of felling work. Hence felling work has been largely or wholly done by hand.

According to this invention, this well-known type of sewing machine is been reconstructed so that it can do felling work quickly and accurately, with a great saving in cost.

According to one feature of my invention, the curved needle is oscillated laterally in its forward piercing stroke from right-to-left and in a rear reverse stroke from left-to-right, thus reversing the usual direction of the piercing stroke of the needle.

According to another feature of my invention, the upward longitudinal bight is formed only in the lower layer or layers of the work, at the right of the top layer or layers, and the top layer of layers are located upon the left shoulder or wall of the upward longitudinal bight.

Hence, in sewing a lining to work which consists of a pre-sewed tubular sleeve body, as one example, it is necessary to mount only the edge-portion of the turned sleeve-body on the work-table, and the doubled front edge of the sleeve is at the right, as viewed at the front of the machine. The main part of the turned sleeve-body and the main part of the lining are off the work support. The longitudinal bight is formed only in two layers of the turned sleeve body, one of said layers being said temporarily exposed cylindrical flap of the turned and tubular sleeve-body. The two layers of the doubled lining rest upon the left wall or shoulder of the longitudinal bight which is formed only in the two layers of the turned sleeve body. Said bight is formed at the left of the doubled edge of said turned sleeve body. In its lateral right-to-left piercing stroke, the curved needle first penetrates the cylindrical flap of the turned sleeve body and the needle then penetrates the two layers of the lining which are adjacent its doubled edge.

At the end of said piercing stroke, the looper engages the loop of needle thread and the looper transfers said engaged loop of needle thread from left to right, so that the loop of needle thread is in position to engage with the needle thread in the next right-to-left piercing stroke of the needle. For this purpose, the action of the looper has been greatly modified. A series of blind felling stitches are thus formed, in which the loops of the needle thread overlap the doubled edge of the lining, and said loops are directed forwardly and to the left of the points at which said felling stitches engage the exposed flap of the tubular sleeve body.

In certain classes of work, these felling switches need not be blind stitches.

It is well-known to connect the layers of the work by temporary basting stitches, which are subsequently removed from the finished work and this can be done in doing felling work by the improved machine.

The invention is further explained in the following drawings and description. In this specific illustration, the machine has a curved oscillating needle, an oscillated longitudinal rib and many other specific features. The invention is not limited to the type of machine which is shown as a highly preferred embodiment.

Fig. 1 is a front elevation of the improved machine, whose operation results in the improved method.

Fig. 2 is an end elevation of Fig. 1. Fig. 2 is taken at the left of Fig. 1.

Fig. 3 is a horizontal section on the line 3—3 of Fig. 2. It shows respective extreme position of the mechanism for operating the looper, in full lines and in broken lines.

Fig. 4 is a longitudinal vertical section on the line 4—4 of Fig. 3.

Fig. 5 is a detail perspective view of some of the parts of the machine. The view corresponds to Fig. 10. The needle is at the end of its right-to-left piercing stroke. The looper is in its extreme rearward position, and as viewed at the front of the machine, the looper is at the right of the rib.

Fig. 6 shows the parts of Fig. 5, in the positions of Fig. 8. The needle has commenced its reverse left-to-right stroke.

Fig. 7 is a detail front view, showing the bight-forming rib in vertical section. The needle is shown at the end of its right-to-left piercing stroke, in which it has pierced three layers of the work. The looper is shown anterior its position in which it engages the loop of needle thread.

Fig. 8 is similar to Fig. 7. Fig. 8 shows the needle shortly after the beginning of its reverse left-to-right stroke and prior to the end of said reverse stroke. The looper is shown with its long finger in the respective loop of needle thread.

Fig. 9 is similar to Figs. 7 and 8. Fig. 9 shows the needle at the end of its reverse left-to-right lateral stroke. It also shows how the looper has shifted the next-preceding loop of needle thread, so that the needle can pass through said next-preceding loop of needle thread, in the next right-to-left piercing stroke of the needle.

Fig. 10 shows the needle at the end of the next right-to-left piercing stroke, in which the needle passes through the next-preceding loop of needle thread, in order to form the respective chain stitch.

Fig. 11 is a longitudinal vertical section on the line 11—11 of Fig. 2.

Fig. 12 is a longitudinal vertical section on the line 12—12 of Fig. 2.

Fig. 13 is an elevation partially in section, on the line 13—13 of Fig. 11.

Fig. 14 is a perspective view, partially in longitudinal and lateral vertical cross-section, which shows the visible parts of the chain stitches which are at the rear or concealed portion of the work.

Fig. 15 is an end-view, partially in lateral vertical cross-section, which generally shows the old-style machine, in which the lateral piercing stroke of the needle is from left-to-right.

Fig. 16 is a perspective view which shows the location of the visible parts of the chain stitches which are formed by the old-style machine.

Fig. 17 shows how a lining is sewed to the tubular turned cloth body of a sleeve by a felling stitch.

The machine has an arm or head 1, a frame F, a work-support H, and a base B. As shown in Fig. 3, the arm or head 1 is fixed detachably to frame F by releasable fastening members 39 and 39a.

Fig. 3 shows the main shaft 38 of the machine, which is parallel to the lateral plane which is shown in Fig. 1. Fig. 1 shows the usual hand-wheel 2 and the usual drive-pulley 3, which are fixed to said shaft 38.

It is well-known to regulate the vertical position of the work-support H, relative to the lateral path of the needle, in order to regulate the depth of the stitch, so that this detail does not require any detailed description. As shown in Fig. 2, the work-support H is pivoted in the usual manner at Ha to the frame of the machine. The angular position of work-support H is adjusted by known adjusting means Hb, which are described in said prior patents. The hand-operated means 4, for operating said adjusting means Hb, are shown in Fig. 1. Said means 4 include a turnable knob 5 which is turned manually, in order to regulate the position of work-support H and the depth of the stitch. Said knob 5 has teeth, not shown. Additional teeth, not shown, are provided in lever 6 which is pivoted at 7 to arm 1. A tension spring 8 keeps these teeth of knob 5 and lever 6 in mesh, so that lever 6 keeps knob 5 in its adjusted position, although knob 5 can be turned by hand while said teeth are in mesh.

Fig. 1 and Fig. 2 show the usual discs 9 and 9a, between which the needle thread 1 is led over the usual guide to the curved needle N. These discs 9 and 9a keep thread 1 under tension anterior needle N. Disc 9a is fixed to arm 1. Disc 9 is laterally slidable relative to disc 9a. A compression spring 10 urges slidable disc 9 towards disc 9a, which may be turnable or non-turnable. This detail is well-known and does not require further illustration.

The upper end of the curved needle N is releasably fixed by clamping member 11b and screw 11c to the lower end of needle arm 11.

As shown in Fig. 1, the upper end of needle-arm 11 is fixed to one leg of a resilient clamping yoke 11a, whose legs are clamped by screw 56 to the usual longitudinal needle shaft 12. This needle shaft 12 is rocked or oscillated, in order to oscillate the curved needle N, by means which are later described.

Fig. 1 also shows the usual needle-plate 14, which is fixed rigidly to arm 1 by a fastening screw 15.

Fig. 2 shows the usual longitudinal slot 21 of the needle plate 14, in which the feed-dog 22 operates in the usual manner, in intermittent longitudinal feeding strokes, in order to feed the work longitudinally, namely, in the plane of Fig. 2. The bight is formed intermittently in the work by the usual rib R, which is moved intermittently upwardly through the slot 21, in order to form the bight which is shown in Figs. 7—10 inclusive. Of course, the needle N is oscillated in its piercing stroke and reverse stroke while the longitudinal feed of the work is temporarily discontinued. The means for operating the rib R are not shown, because they are well-known and described in said prior patents.

The work is fed under the needle-plate 14 in the usual manner and it remains under the needle-plate 14 in the usual manner, save when the rib R is operated to form the upward and longitudinal bend or bight in the work.

Figs. 7, 8, 9, 10 illustrate work which has a lower layer 74, which is doubled at edge EB to provide an upper layer 75. Said upper layer 75 is doubled at edge EC to provide a flap or layer 75a, which is between upper layer 75 and lower layer 74. As above noted, Fig. 7 shows the needle N at the end of its right-to-left piercing stroke, and Fig. 8 shows the needle N shortly after the beginning of its reverse left-to-right stroke. The doubled edge EB is located to the left of the point of needle N, when needle N is at the end of its right-to-left piercing stroke.

The longitudinal bight is formed in layer 74, so as to provide a bight which has two legs in layer 74. In its piercing stroke, needle N pierces and passes through both legs of said bight in layer 74. In said bight, the

layers 75 and 75a are upwardly bent, so that each said layer 75 and 75a has a single leg. In its piercing stroke, the needle N first passes from right-to-left through both legs of the bight which is formed in layer 74; and then successively through the single legs of the bight in layers 75a and 75, close to the doubled edge EC of said layers 75a and 75. As previously noted, when the work is a sleeve, the body of the sleeve has an inturned flap which is exposed. The layer 74 corresponds to said exposed flap of the sleeve in the operation of the machine. The layer 75 corresponds to the top layer of the lining during the sewing operation, and the layer 75a corresponds to the inturned flap of the lining.

The needle penetrates the two walls of the bight close to the top or peak of said bight, and it penetrates the layers 75 and 75a close to their doubled edge E. As previously explained, if blind felling stitches are used to sew a lining to a sleeve, the needle penetrates only the exposed flap of the sleeve-body and does not penetrate the sleeve-body itself. However, if the sleeve-body is of sufficient thickness, the needle may penetrate both the flap and the sleeve-body. Fig. 7 shows the formation of a blind felling stitch, in which the needle penetrates the layer 74 between its top and bottom faces, so that the felling stitches will not be visible at the exposed face of the layer 74. However, if layer 74 is thin, exposed felling stitches will be formed, instead of blind felling stitches, and the invention is not limited to the formation of blind felling stitches.

It is clear from Fig. 7 that the main portions of layers 75 and 74, which are at the left of the bight in Fig. 7, are off the work table, and that only the right edge-portion of the thicker part of the work need be on the work table.

Fig. 7 shows the position of the looper L at the left of the bight, at the end of the lateral right-to-left stroke of the needle N.

Fig. 8 shows the position of the needle N, shortly after the beginning of its reverse lateral left-to-right stroke. A loop Na of the needle thread has been formed in the usual manner. The finger 23 of the looper L has entered said loop Na. The arrows in Figs. 7 and 8 indicate the respective direction of the respective lateral strokes of the needle N.

Fig. 9 shows the needle N at the end of its left-to-right reverse stroke. The arrow in Fig. 9 indicates the direction of the next right-to-left lateral stroke of the needle. Fig. 9 shows how both fingers 23 and 24 of looper L have entered and enlarged the loop Na during the left-to-right reverse stroke of the needle, and that the looper L has shifted said enlarged loop to the right of the bight in layer 74, and that said enlarged loop Na has been shifted longitudinally forwardly, so that the needle N will enter said enlarged and longitudinally shifted loop Na in the next lateral right-to-left piercing stroke of the needle, before the needle will penetrate the bight in layer 74.

Fig. 10 shows the needle Na at the end of its next right-to-left piercing stroke, or close to the end of said piercing stroke. As shown in Fig. 10, the needle N has passed successively through the enlarged loop Na, through both walls or legs of the bight in layer 74, and through both layers 75 and 75a and the looper L has been moved out of the loop Na shortly after the needle N has passed between the loop fingers 23 and 24 to enter the loop Na.

A succession of felling chain-stitches S is thus formed.

Fig. 14 shows the felling chain-stitches S in the finished work. The work is held in Fig. 14 in the same position as during sewing in the machine illustrated herein. The chain-stitches S are at the right edge of the thicker part of the work, which has the greatest number of layers.

Fig. 16 shows the finished work in the position in which it must be held in forming felling stitches Sa in the old style chain-stitch machine which has heretofore been

generally used for this type of work. These stitches Sa are at the left edge of the thicker part of the work.

If the layers 75 and 74 are of considerable lateral dimension, it would be impossible to put them on the work-table at the right of the bight. In the improved machine, only a short lateral part of the work need be put on the work-table. Hence if a lining is to be sewed upon a sleeve as explained herein, the sleeve is inserted from left-to-right into the machine so that the edge of the sleeve body and its flap are upon the fingers 16 and 16a later mentioned, but the main body of the sleeve is off the work-table and to the left of the work-table. The doubled edge of the lining is also inserted from right-to-left into the machine above said fingers 16 and 16a, with the two layers of the lining resting upon the two layers of the sleeve-body and with the main body of the lining in a position to the left of the work-table.

Fig. 17 shows a lining 81 sewed by felling stitches S to the exposed inturned flap 82 of a sleeve 80. This sleeve 80 is shown in the position in which the felling stitches S are formed in the improved machine. The right edge-portion of flap 82 corresponds to layer 74 in Figs. 7-10. The layers 75 and 75a correspond to the two layers of the inturned lining 81. If blind felling stitches are formed, the needle penetrates the two legs or walls which are formed in the sleeve-flap 82, in the manner shown in Figs. 7-10, and the needle then penetrates the respective single upwardly-bent legs of the inturned lining. The left edge of sleeve flap 82 is not shown in Fig. 17, because it is under the right doubled edge portion of the lining 81.

Fig. 1 shows the usual identical work-supporting fingers 16 and 16a, on which the work is directly slidably supported below the needle-plate 14. These fingers 16 and 16a are connected to the usual and identical associated parts, which include the usual arm or levers 18, which have the usual extensions 18a.

Thus, Fig. 2 shows that the finger 16 is pivoted at 17 to an arm or lever 18, which is pivoted at 19 to work-support H. Said arm or lever 18 has the usual extension 18a. A tension biasing spring 20 which is connected to work-support H and extension 18a, biases arm 18 to bias finger 16 upwardly, in the usual manner.

As shown in Fig. 3, this looper L has the usual long looper finger 23 and the usual short looper finger 24.

As shown in Figs. 2 and 3, one end of the looper L is fixed by a fastening member 25, to an angular extension 26 of a looper-rod 27, which has an integral ball 27a. As shown in Fig. 11, this ball 27a of the looper L fits turnably in a ball-shaped recess of a yoke which consists of the yoke-members 28 and 28a. As shown in Fig. 2, these yoke-members are fixed detachably to each other by the usual fastening members 28b. As shown in Fig. 11, the yoke member 28a has a sleeve 30s, which has a cylindrical bore. This sleeve 30s is turnable on a cylindrical pivot-stud 30. This pivot-stud 30 has a threaded co-axial extension 30a, which is screwed into a threaded recess of a bushing 40, which has a cylindrical outer wall which is turnable in a cylindrical socket of frame F. Said pivot-stud 30 and its threaded extension 30a have a common pivot axis, which is eccentric relative to the axis of the outer cylindrical wall of bushing 40. Hence, by turning bushing 40 manually in its socket of frame F to a selected adjusted position, the effective longitudinal stroke of looper L can be adjusted, in order to regulate the length of the chain stitch. The bushing 40 is held in its manually adjusted position by the releasable clamping screw 40a.

The ball 27a and said sleeve 30s and said pivot-stud 30 provide an universal joint connection between the looper-rod 27 and said pivoted yoke 28a-28.

As shown in Fig. 2, the inner or left end of the looper-rod 27 is located in a socket 31a of a looper-actuating member 31. This socket 31a of looper-actuating member 31 may be split, resilient, and internally threaded;

The inner or left end of looper rod 27 may be threaded and screwed into said socket 31a.

This split and resilient socket 31a of looper-actuating member 31 may be tightened by a clamp which consists of two clamp parts 32, which are forced towards each other by clamping screws 33 and 33a.

As shown in Fig. 2 and Fig. 3, the inner end of the looper-operating member 31 is fork-shaped to provide two legs which are pivoted to a hollow bushing 35 by a pivot-pin 34.

This hollow bushing 35 is turnable on an inner stud-shaft 36. As shown in Fig. 3, this stud-shaft 36 has a co-axial threaded end 36a, which is screwed into a threaded recess of an eccentric wheel 37, which is fixed to and which is eccentric relative to shaft 38, which is continuously turned in the same direction while the machine is operating. This eccentric wheel 37 operates the looper and it rocks the needle shaft 12.

The pivot pin 34 is thus shifted back and forth between its respective extreme positions which are shown in full lines and broken lines in Fig. 3, and the looper L is actuated to operate as above described.

The usual feed-dog 22 is operated in the usual four-motion path, in order to intermittently engage and feed the work longitudinally away from the operator towards the rear of the machine.

As shown in Fig. 4, the feed-dog 22 has an extension 22a, which is fixed by screws 41 to one end of a feed-bar 42, which has an annular hub 42a which fits on a part of the periphery of the eccentric wheel 37. As shown in Fig. 3, a spacing collar 53 is located between said hub 42a and a flange of the eccentric wheel 37. The hub 42 is thus located on the eccentric wheel 37 between said collar 53 and another flange of wheel 37. Said wheel 37 is freely turnable relative to the hub 42a, so that hub 42a operates as an eccentric strap.

As shown in Fig. 4 and Fig. 11, the feed bar 42 has a bore in which a pivot pin 43 is located. As shown in Fig. 4, this pivot pin 43 extends into a disc 44, which is fixed to a pivot pin 45. The pivot pin 45 is turnable in a bearing of the frame F. The disc 44 is oscillated by the eccentric wheel 37 about the central axis of the pivot pin 45, which turns in unison with the disc 44 relative to frame F. As shown in Fig. 11, the pivot pin 45 is provided with a split head 55, whose parts are held together by releasable fastening members 55a. The enlarged head 55a prevents the longitudinal shifting of pivot 45 to the right as viewed in Fig. 11. The disc 44 is oscillated during the reciprocating movement of the bar 42, around the axis of pivot 45, in order to raise and lower the feed-dog 22 in timed relation to its longitudinal rearward feeding and return longitudinal strokes. The pin 45 may be fixed to frame F and disc 44 may be turnable on pin 45.

Fig. 1, Fig. 2 and Fig. 4 show the usual rib R, which is oscillated in the usual manner, in order intermittently to form the upward longitudinal bight or bend of the work in the front part of the longitudinal slot 21 of needle plate 14. This rib R is fixed to the rib-shaft 47 which is oscillated in the usual manner. The mechanism for oscillating the shaft 47 of rib R is located in the hollow base B of the machine and is of the usual type, so that it is not shown.

Fig. 4 shows the usual top pressure finger 48 which presses downwardly against the top of the bight of the work which is formed in the slot 21, in order to cooperate with the rib R in forming the bight. As shown in Fig. 3 and Fig. 4, this pressure finger 48 is turnably connected to a lateral pin 50 which is fixed by a screw 51 to the needle plate 14. A torsion spring 52 is located around the pin 50. One end of this torsion spring 52 abuts the pressure finger 48 in order to urge it to turn downwardly.

As shown in Fig. 4, a collar 58 is releasably fixed to the needle rock-shaft 12 by a clamping screw 59, in

order to prevent sliding movement of the needle rock-shaft 12 in its bearing in the frame F to the right, as viewed in Fig. 4. As also shown in Fig. 4, the rock-shaft 12 is provided with a reduced left end 12a. As shown in Fig. 4 and Fig. 12, a hub 60 is provided at one end of a lever or arm 61. This hub 60 is clamped or otherwise releasably fixed to the reduced end 12a of the needle-shaft 12. This arm or lever 61 is oscillated, in order to oscillate the needle-shaft 12.

Fig. 3 and Fig. 4 show another eccentric strap or hub which consists of two parts 62 and 62a, which are held to each other by screws 63. This strap 62—62a is mounted on eccentric wheel 37. This strap 62—62a is used to oscillate the arm or lever 61 and hence to oscillate the needle-shaft 12 by means of intermediate parts. The wheel 37 rotates freely relative to this strap 62—62a. As shown in Fig. 3, these parts 62 and 62a of said hub or strap have inner concave walls which interfit with a convex part of the periphery of eccentric wheel 37, so that said strap or hub 62—62a cannot shift relative to eccentric wheel 37 in a direction parallel to its actuating shaft 38.

Fig. 12 shows bearing members 71 and 72, which are connected to each other by screws 73 and 73a. Figs. 4 and 12 show a member 69, which has a general ball-shape and which is provided with opposed flat walls. Said assembled bearing members 71 and 72 have a concave socket, in which the spherical part of the member 69 fits turnably. Said member 69 has a pin 70 which is parallel to shaft 12 and which is fixed to the arm or lever 61.

As shown in Fig. 4, the hub-member or strap-member 62 has an extension arm 64. As also shown in Fig. 4, an arm 65 has an end-lug 66 which is fixed releasably to said extension arm 64 by a screw 67. The other end of said arm 65 has an end-lug 66 which is fixed releasably to bearing 71 by a screw 68.

Hence, when the eccentric wheel 37 is turned relative to its strap or hub 62—62a, the member 69, which can turn freely relative to bearings 71 and 72, oscillates the lever 61, whose hub 60 is fixed to extension 12a of shaft 12, thus oscillating said shaft 12 and oscillating the needle N.

Fig. 15 diagrammatically shows the old-style chain-stitch machine which has been generally used for this type of sewing operation. The needle N is shown in Fig. 15 at the beginning of its left-to-right piercing stroke.

The needle-plate 14 is held fixed by the usual plate P.

The member 64a which is shown in Fig. 4 is an optional member which extends through a bore of arm 65 and which abuts the adjacent flat face of the member 69.

In the example of Figs. 7-10, the work consists of a single piece of folded fabric, in which a hem is formed by the felling stitches.

In the example of Fig. 17, the work consists of two pieces of fabric, which are sewed to each other by the felling stitches.

Hence the work may consist of a single piece of fabric, or a plurality of pieces of fabric.

In each example, the work has an edge over which the felling stitches are formed. In the example of Figs. 7-10, this edge is the edge EC. In the example of Fig. 17, this edge is the right edge of the lining 81. For convenience, this edge is designated as the felling edge.

In each example, the work has a bight forming portion in which a transverse bight is formed. In the example of Figs. 7-10, this bight-forming portion is between the felling edge EC and the edge EB. This bight forming portion is of sufficiently small width to pass over the work-table or to pass through the feeding space of the machine which is above the work-supporting fingers 16 and 16a.

The other lateral portion of the work, which is between the edges EC and EB in the example of Figs. 7-10,

usually has a width or lateral dimension which is much greater than the width of the work table or the width of the feeding space of the machine which is above the work-supporting fingers 16 and 16a.

As viewed in Fig. 1, the work-supporting fingers 16 and 16a and the rib R are at the left edge of the machine, and if the work is a sleeve the part of the work at which the bight is formed and in which the felling operation is performed, is moved into position from left to right, with the wide part of the work depending at this left edge of the machine. This left edge is designated as the outer edge or free edge of the machine. Fig. 1 shows the needle N at the end of its reverse stroke, which corresponds to the position of Fig. 9.

The drawings are substantially to scale, with different scales in the respective drawings, and reference is made thereto for additional disclosure.

The looper rod 27 is tilted relative to its mount 28—28a, which turns around a lateral axis. The looper rod 27 is also turned around its axis, relative to its mount 28—28a.

Thus, when the hollow bushing 35 and its offset pivot 34 are in the full-line position of Fig. 3, the looper-rod 27 is also in its full-line position of Fig. 3, and the looper L is in its extreme forward position of Fig. 9, and the needle N is at the end of its reverse left-to-right stroke which is shown in Fig. 9. Fig. 9 also shows, in broken lines, the position of the hollow bushing 35 and of the looper-rod 27, when the eccentric 37 is turned 180° from its position of Fig. 3.

The pivot 34 is in its extreme forward position, in its full-line position at Fig. 3. At this time, and as shown in Fig. 4, the feed-dog 22 is in its extreme forward position and it is ready to begin its longitudinal rearward feeding stroke. Hence the work is fed while the needle is out of the goods.

I claim:

1. In a chain-stitch sewing machine which has a frame and a front end and a longitudinal direction of feed of the work through said machine from front to rear, the combination of the elements later stated herein, namely: a fixed needle plate which is fixed to said frame and has a longitudinal slot; work-supporting means located below said needle plate and adapted to press the work upwardly against said slot, said work-supporting means having a free edge which is at the left edge of said work-supporting means as viewed at the front of the machine so that the work can be inserted from left-to-right between said needle plate and said work-supporting means as viewed at the front of the machine; a longitudinal needle rock-shaft located above said needle-plate; rock-shaft actuating means for oscillating said needle rock-shaft; a needle arm having an upper end fixed to said needle rock-shaft, a curved needle whose upper end is fixed to said needle arm, said needle arm and said curved needle being located above said needle-plate and being movable back-and-forth in a lateral plane relative to said slot; a feed-dog located above said needle plate and operative to feed said work longitudinally and rearwardly away from the front of the machine; feed-dog actuating means adapted to operate said feed-dog in intermittent feeding strokes; a looper which has a front long point and a short front point and which is turnable about a longitudinal axis and which is also longitudinally movable back-and-forth relative to said lateral plane and which is also movable in said lateral plane, and looper-actuating means for turning said looper and moving said looper longitudinally back-and-forth and laterally back-and-forth; a rib which is upwardly movable to an operative position to force the part of the work which is below said slot to a position above said slot, said rib being also downwardly movable to a lower idle position in which said part of said work is below the top of said slot; rib-actuating means for moving said rib between its said operative and its said idle positions; said rib having a top face which has an

inverted V-shape with a left and longitudinal wall and a right and longitudinal wall and a peak at the top of said top face; said rib being located and its top being shaped relative to said work-supporting means to provide a V-shaped bight in the lower part of the work on both said walls and only to bend the upper part of the work at said left wall in upwardly bent legs when said rib is in its said operative position; common actuating means connected to said rock-shaft actuating-means and to said feed-dog actuating means and to said looper-actuating means and to said rib-actuating means, said common actuating means being operative and timed to produce a sequence of operations as follows:

(a) to operate the feed-dog in a respective feeding stroke while the rib is in its idle position and while the needle is out of the work;

(b) to move the rib upwardly to its upper position to form said bight and said upwardly bent legs;

(c) to move the needle from right-to-left in a piercing stroke to pass the needle through said bight and said upwardly bent legs and to the left of said peak to the extreme left position of said needle while said looper is at the left of the right end of said needle and said looper is laterally intermediate said right end and the left point of said needle and while said looper is located rearwardly of said needle;

(d) to move said needle reversely in a part of its left-to-right reverse stroke while throwing out a new loop of needle-thread from the needle to the left and while moving said looper longitudinally forwardly and while passing only the long point of said looper through said new loop and while locating said long point to the left of said peak;

(e) shifting said looper from left to right in unison with said needle in the remainder of its reverse stroke to shift the looper from the left of said peak to the right of said peak while turning said looper to insert both of its points into said new loop and to shift said new loop into position to be engaged by the needle in the next right-to-left piercing stroke and removing said points from said new loop at the right of said peak, thus forming, by the successive sequences of said operation, a series of interchained loops of needle-thread in which the loops of needle thread are passed through the thicker part of the work at points which are spaced longitudinally forwardly and are to the left of the points at which the loops of needle thread are passed through the thinner part of the work.

2. A combination according to claim 1, in which the looper has supporting means, which include a looper-rod which has a ball, a split yoke which comprises two yoke-members which are fixed to each other and which have a ball-shaped recess in which said ball is turnable, one of said yoke-members having a sleeve fixed thereto, said sleeve being perpendicular to said looper rod, said sleeve being mounted turnably on a pivot-stud which is fixed to a turnable, cylindrical bushing which is turnably mounted in said frame, said pivot-stud being eccentric relative to said bushing, and means for releasably fixing said bushing to said frame.
